UNITED STATES PATENT OFFICE

2,007,706

DROP STAFF BRAKE MECHANISM

Percy B. Camp, Maywood, Ill., assignor to Universal Draft Gear Attachment Co., a corporation of Illinois

Application August 2, 1934, Serial No. 738,027

5 Claims. (Cl. 74—510)

The invention relates to brake mechanism of the so-called multi-power type, especially adapted for use on flat cars, the staff being vertically movable in order that it may be lowered out of the way of the lading.

The objects of the invention are to simplify the construction, particularly with reference to the mounting of a gear pinion with the staff, and to provide for the secure support of the staff in its elevated position.

In the accompanying drawing illustrating a desirable form of embodiment of the invention,

Fig. 1 is a detail, longitudinal section of a car body and its brake actuating mechanism, the staff being shown in elevated position.

Fig. 2 is a detail section on the line 2—2 of Fig. 1;

Fig. 3 is a detail section on the line 3—3 of Fig. 2;

Fig. 4 is a view in perspective of one of the pivot pins for carrying the staff supporting stirrup;

Fig. 5 is a view in perspective and partly in section of an element of the housing for the brake mechanism; and

Fig. 6 is a view in perspective of the staff supporting stirrup.

The floor of a flat car is represented at 10 and the end sill thereof at 11. The brake actuating mechanism comprises a housing element 12, secured to the end sill, as indicated at 13, and carrying a gear wheel 14 with which is connected a winding drum 15 to which the draw chain 16 of the brake is attached. This mechanism further comprises a housing element 17 within which is journaled a shrouded pinion 18 which meshes with the gear 14. The element 17 bears a pair of bushings 19, 20, for the upper and lower journals of the pinion 18. Immediately above these journal surfaces of the pinion are a pair of shoulders 21, 22, which rest upon the journal bearings for the pinion. The gear 14 engaging the pinion between its shrouds prevents its upward movement.

The socket of the pinion 18 is square and slidably receives the squared brake staff 23. The staff may be lowered to bring the hand wheel 24 to the level of the car floor, when it is not in use, and when raised its lower end rests upon a swinging U-shaped stirrup 25, which is carried by pivot pins 26 setting through side walls of the elements 17, and outstanding lugs 27 carried by this element. The pivots 26 are non-rotative and are shown as a flat plate, their sockets 28 being

of corresponding form. The sockets 29 in the stirrup arms are sufficiently large to permit turning movement of the stirrup about the pins 26, but each is provided at its upper margin with a slot 30 for receiving the upper margin of the pivot pin, as a key, thereby preventing the turning of the stirrup.

When the stirrup is so positioned that the pivot pins occupy the slots 30, the cross arm of the stirrup is directly in line with the staff 23 and holds the latter in its elevated or operative position. When it is desired to lower the staff the stirrup is raised sufficiently to free its slots 30 from the keys, and it is then swung forwardly, permitting the staff to descend through the pinion 18. When the staff is again raised to clear the stirrup the latter swings backwardly by gravity until its slots 30 register with the pins 26, whereupon it comes to rest and is securely locked in staff-supporting position until again manually released.

At 31 is conventionally shown means for holding the brake staff against rotation, and at 32 a stud through the lower end of the staff to limit its upward movement.

While the disclosed embodiment of the invention is highly efficient, it may obviously be variously changed within the scope of the appended claims.

What I claim is:

1. In a drop staff car brake, in combination, a vertically movable staff, a housing through which the staff may slide, a U-shaped oscillatable stirrup for supporting the staff in its upper position, vertical lugs formed on the housing adjacent the location of the staff, pivots extending through the lugs and the arms of the stirrup, one of such pivots being fixed against rotation relatively to one of the parts it unites, the pivot aperture of the other part having a radial extension for receiving and holding the pivot when the cross member of the stirrup is in the path of movement of the staff.

2. In a drop staff car brake, in combination, a vertically movable staff, a housing through which the staff may slide, a U-shaped oscillatable stirrup for supporting the staff in its upper position, vertical lugs formed on the housing adjacent the location of the staff, pivots extending through the lugs and the arms of the stirrup, one of such pivots being out of round and non-rotative, the pivot aperture in the stirrup arm having a radial extension for interlocking with such pivot when the cross member of the stirrup is in the path of movement of the staff.

3. In a drop brake for cars, a suitable housing, a staff vertically movable through the housing, a stirrup pivoted to the housing for supporting the staff, a pivot pin fixed in the housing and having a rib on its upper face, and the pivot socket in the stirrup having a recess at its upper side for receiving the rib when the stirrup is in staff-supporting position.
4. In a drop staff car brake, in combination, a staff, a housing through which the staff may slide, a stirrup pivotally connected with the housing for supporting the staff, the pivot pin of the stirrup being out of round and fixed to one of the connected parts, the socket in the other part having a radial recess for engaging and retain-

ing the pivot when the stirrup is in supporting position.

5. In car brake mechanism, in combination, a vertically movable brake staff, a U-shaped stirrup for supporting the staff in its elevated position, a fixed pivot located laterally of the staff upon which the stirrup is suspended, the stirrup being oscillatable about the pivot from a position immediately below the staff when raised to the remote side of the staff when lowered, the pivot aperture of the stirrup having a lateral recess positioned to receive and interlock with the pivot when the cross-member of the stirrup is beneath the staff.
